(75) Inventor: **Hideaki Nakanishi**, Toyohashi (JP)

Primary Examiner—Alan P. Douglas

(73) Assignee: **Emhart LLC**, Newark, DE (US)

Assistant Examiner—Clare E. Heflin

(**) Term: **14 Years**

(74) Attorney, Agent, or Firm—Edward D. Murphy

(21) Appl. No.: **29/141,062**

CLAIM

(22) Filed: **Apr. 27, 2001**

The ornamental design for a clip for fastening a mounting member to an automobile, as shown and described.

(51) LOC (7) Cl. **08-08**

DESCRIPTION

(52) U.S. Cl. **D8/382**; D8/386

FIG. 1 is a perspective view of a clip of the present invention;

(58) Field of Search D8/382, 384-393;

FIG. 2 is a front elevational view thereof, the rear elevational view being a mirror image of the front;

411/500, 508-511, 455, 908, 913, 923;
24/297, 703

FIG. 3 is a right side elevational view thereof, the left side being a mirror image of the right side;

(56) **References Cited**

FIG. 4 is a top plan view thereof;

FIG. 6 is a sectional view taken along line 6—6 of FIG. 2;

FOREIGN PATENT DOCUMENTS

FIG. 7 is a sectional view taken along line 7—7 of FIG. 2;

JP 521547 9/1979

FIG. 8 is a front elevational view, similar to FIG. 2, in which the clip is shown connecting the broken line representation of a trim board to the body of an automobile; and,

FIG. 9 is a front elevational view, similar to FIG. 2, in which the clip is shown connecting the broken line representation of a trim board to another body of an automobile.

The broken line representation of the trim board and the body of an automobile in FIGS. 8 and 9 are for illustrative purposes only and form no part of the claimed design.
